UNITED STATES PATENT OFFICE.

WILLIAM B. TOCHER, OF JAMAICA, NEW YORK.

APPARATUS FOR RECEIVING AND DELIVERING MAIL-BAGS.

1,196,177.

Specification of Letters Patent. Patented Aug. 29, 1916.

Application filed March 8, 1916. Serial No. 82,961.

To all whom it may concern:

Be it known that I, WILLIAM B. TOCHER, a citizen of the United States, and residing at Jamaica, Long Island, in the county of 5 Queens and State of New York, have invented certain new and useful Improvements in Apparatus for Receiving and Delivering Mail-Bags, of which the following is a specification, such as will enable those 10 skilled in the art to which it appertains to make and use the same.

This invention relates to railway apparatus for delivering mail bags from a moving train to a station and also for delivering 15 said bags from the station to the train, and the object thereto is to provide an improved apparatus for this purpose, whereby mail bags may be more safely and easily transferred, as described, and without danger of 20 injuring said bags or their contents in any way.

The invention described and claimed herein is an improvement on that described and claimed in U. S. Letters Patent No. 627,294 25 granted to H. J. Brown June 20, 1899, and said invention is fully disclosed in the following specification, of which the accompanying drawing forms a part, in which the 30 separate parts of my improvement are designated by suitable reference characters in each of the views, and in which:—

Figure 1 is a side elevation showing the apparatus which I employ and its method of use; Fig. 2 a plan view thereof partly in 35 section; Fig. 3 a cross section on the line 3—3 of Fig. 1; Fig. 4 a plan view of the construction shown in Fig. 3; Fig. 5 a view similar to Fig. 3 but showing only part of the construction and showing the same on an enlarged scale; Fig. 6 a section on the line 40 6—6 of Fig. 1; Fig. 7 a section on the line 7—7 of Fig. 4 and on an enlarged scale; and, Fig. 8 a view of the opposite side of a part 45 of the construction shown in Fig. 6.

In the drawings forming part of this specification, and in Figs. 1 and 2 thereof, I have shown at 10 the rails of a railway track and at 11 a mail car and, in the practice of my invention, I provide adjacent to a 50 station two standards or supports 12 and 13 which are arranged longitudinally of the track and at one side thereof and at a predetermined distance apart.

The standard 13 is set closer to the track 55 than the standard 12, and the standard 12 is

much higher than the standard 13, and secured to the tops of said standards is a cord or cable 14 preferably of wire, and by means of the fact that one of said standards or supports is higher than the other, the said cord or cable is maintained at an inclination, the end thereof which passes over or is connected with the standard or support 12 being 60 higher than the other end. 65

Secured to the side of the car 11 adjacent to a door 15 is an angle plate bracket 16 below which is secured a housing bracket 17, and mounted between said brackets is an arm 18 adapted to swing in a horizontal plane. The arm 18, in the construction shown, is composed of two parallel parts and the inner end thereof is provided with a vertical member 19 which is pivoted in the brackets 16 and 17, and the lower end thereof passes into the bracket 17 and is provided with a beveled gear 20, and passed outwardly through the side of the car and into the bracket 17 is a shaft 21 provided at its outer end with a gear 22 which meshes with the gear 20 and at its inner end with a crank 23 by means of which the arm 18 may be swung horizontally. 70 75 80

Mounted on the outer end portion of the arm 18 is a yoke-shaped attachment 24 having a top plate which projects outwardly and one side of which is provided with a hook 25 which opens upwardly and the outer end of the arm 18 is provided with a 90 fork 26, and inwardly of the fork 26 and under the top plate of the yoke-shaped attachment 24 is mounted a stop device 27.

The standard 12 is composed of two spaced parts in the form of construction shown, or 95 provided with a central slot 28 in which is pivoted an arm 29 to which is pivoted a curved supplemental arm 30 provided in its bottom surface or edge with spaced recesses 31, and the standard 12 is provided with a 100 cross pin 32 which operates in connection with said recesses, and by means of this construction the arm 29 may be raised or lowered, and adjusted into different positions, and any desired number of the recesses 105 31 may be employed, and the object of the recesses 31 and pin 32 is to lock the arm 29 in its horizontal position, as shown in Fig. 6, which is its operative position, and also to hold said arm in its lowest position for 110 the purpose hereinafter described.

The arm 29 is provided on one side there-

of and near its outer end with a V-shaped stud 33, and the arm 30 is provided on one side thereof with a stud 34. I also provide a bag carrying or suspending device 35 comprising a V-shaped frame the side arms of which are provided near their lower ends with inwardly directed members 36 to which are pivoted supplemental arms 37 having cam-shaped heads 38. The arms 37 are adapted to fold inwardly as shown in dotted lines in Fig. 5, but their cam-shaped heads 36 prevent their folding outwardly beyond the horizontal position as indicated in full lines in said figure.

15 One arm of the bag carrying device 35 is provided with an extension 39 at the top of which said arm is provided at its opposite sides with projecting lugs 40, and at the top of the extension 39 is a projecting shoulder 41, and the bag carrying device 35 may be attached to the arm 18 by slipping the head of the extension 39 of one side of said bag carrying device into the fork 26 at the end of said arm, as shown in Fig. 3, in which position of said bag carrying device the head of the extension 39 strikes against the stop device 27 and the shoulder 41 fits under the top plate of the yoke-shaped attachment 24 and the lugs 40 bear on the sides of the fork 26 at the outer end of the arm 18.

20 Two of the bag carrying devices 35 are employed, one in connection with the arm 18 for delivering a mail bag at a station and the other in connection with the arm 29 of the standard 12 for delivering a mail bag to the train or car of a train.

25 The extension 39 of one arm of the bag carrying device is provided with a bag hook 42 which is loosely suspended therefrom and from which a mail bag 43 may be suspended, and when it is desired to deliver a bag from the train to a station, one of the bag carrying devices 35 is suspended from the arm 18 as indicated in Fig. 3, and the position of said arm with reference to the cable 14 is so adjusted that as the train passes the cable 14 passes in between the supplemental arms 37 of the bag carrying device suspended from the arm 18, in which operation said cable raises said arms, or one of them, and as the train proceeds, and by reason of the relative position of the cable and the track, and the fact that the height of said cable between the standards 12 and 13 gradually increases, the bag carrying device 35 will be drawn out from, or disconnected from the arm 18, and said bag carrying device will be left suspended on the cable 14, between the standards 12 and 13.

30 In delivering a bag to the train, one of the bag carrying devices 35 is suspended from the V-shaped stud 33 at the end of the arm 29 as indicated in Fig. 6, and one side arm of said bag carrying device strikes

against the stud 34 on the arm 30 and this holds the bag carrying device 35 in proper position, and as the train proceeds on its way after depositing a bag at the station, as above described, the arm 18 strikes the bag carrying device 35 suspended from the arm 29 of the standard 12 and detaches said bag carrying device from the stud 33 and from the arm 29 and the said bag carrying device drops into the hook 25 at the end of 75 the arm 18 and may be removed therefrom by the operator on the train.

35 The object in being able to lower the arm 29 of the standard 12 is to facilitate the suspending of the bag carrying device 35 therefrom, as will be readily understood.

40 From the foregoing description, it will be understood that the main feature of this improvement in apparatus of the class specified is the bag carrying or suspending device 35, and the construction and operation of the arms 18 and 29 and the means whereby the bag carrying device 35 is employed in connection with said arms, and while I have shown and described the construction which 90 I prefer in carrying my invention into effect, the invention is not limited to the exact details of construction herein shown and described, and changes therein and modifications thereof may be made, within the 95 scope of the appended claims, without departing from the spirit of my invention or sacrificing its advantages.

45 Having fully described my invention, what I claim as new and desire to secure by Letters Patent, is:—

1. In an apparatus of the class described, a bag carrying and suspending device comprising a V-shaped frame the side arms of which are provided near their ends with 105 supplemental pivoted arms adapted to fold inwardly but normally held in a horizontal position, and means for detachably supporting said device adjacent to the side of a car in a plane at right angles thereto and with 110 the side arms directed downwardly.

2. In an apparatus of the class described, a bag carrying and suspending device comprising a V-shaped frame, the side arms of which are provided near their ends with 115 supplemental pivoted arms adapted to fold inwardly but normally held in a horizontal position, one of said arms being also provided with an extension from which is loosely suspended a bag holder.

3. In an apparatus of the class described, an arm connected with a movable car and adapted to swing horizontally, said arm being provided at its outer end with a fork, and a bag carrying and suspending device 125 comprising a V-shaped frame, the side arms of which are provided near their ends with inwardly directed supplemental arms which are pivoted thereto and adapted to fold inwardly but which are normally held in a 130

horizontal position, one of the side arms of the V-shaped frame being provided with a part adapted to be detachably inserted into said fork.

5 4. In an apparatus of the class described, an arm connected with a car and adapted to swing horizontally, said arm being provided at its outer end with a fork and one side thereof being provided adjacent to said end

10 with a hook device which opens upwardly.

5. In an apparatus for delivering mail bags from a moving train to the station and from the station to the train, a cable supported longitudinally of the track at one 15 side thereof by standards, one of which is higher than the other, an arm connected with a car adjacent to a door therein and provided with a hook device, another arm connected with the higher of said standards, 20 and two similar bag carrying and suspend-

ing devices one of which is adapted to be detachably connected with the arm which is connected with the car and to be detached therefrom by said cable as the car passes the station and the other of said bag carrying 25 and suspending devices being adapted to be detachably connected with the arm of said standard and to be detached therefrom by the arm connected with the car as the car passes the standard and to be supported by 30 said hook device.

In testimony that I claim the foregoing as my invention I have signed my name in presence of the subscribing witnesses this 4th day of March, 1916.

WILLIAM B. TOCHER.
